LOCK

Louis Ditchik, New York, N. Y.

Application September 2, 1953, Serial No. 26,671

Term of patent 3½ years

(Cl. D50—8)

To all whom it may concern:

Be it known that I, Louis Ditchik, a citizen of the United States, residing in New York city, county and State of New York, have invented a new, original, and ornamental Design for a Lock, of which the following is a specification, reference being had to the accompanying drawing, forming a part thereof, in which:

Fig. 1 is a front elevational view of a lock showing my new design;

Fig. 2 is a rear elevational view thereof;

Fig. 3 is a side view thereof;

Fig. 4 is a top view thereof;

Fig. 5 is a bottom view thereof; and

Fig. 6 is a cross-sectional view taken substantially on line 6—6 of Fig. 1.

I claim:

The ornamental design for a lock, as shown.
